COMBINATION SCISSORS AND KNIFE SHARPENER

Richard F. Curley, Sr., Baltimore, Md., assignor to National Products Co., Inc., Baltimore, Md., a corporation of Maryland

Application December 28, 1956, Serial No. 44,348

Term of patent 3½ years

(Cl. D37—1)

Fig. 1 is a side elevation of a combination scissors and knife sharpener, showing my new design;

Fig. 2 is an edge view of Fig. 1; and

Fig. 3 is a section on the line 3—3 of Fig. 1.

The reverse side of the device is substantially similar to that shown in Fig. 1.

I claim:

The ornamental design for a combination scissors and knife sharpener, as shown and described.
